(57) CLAIM

The ornamental design for a flat panel monitor, as shown and described.

DESCRIPTION

FIG. 1 is a front perspective view of a flat panel monitor showing our new design;

FIG. 2 is a rear perspective view thereof;

FIG. 3 is a front view thereof;

FIG. 4 is a rear view thereof;

FIG. 5 is a side view thereof;

FIG. 6 is a bottom view thereof; and,

FIG. 7 is a top view thereof.

The broken lines are shown in the views for illustrative purposes only and form no part of the claimed design.
